WITNESS:

UNITED STATES PATENT OFFICE.

PAUL JOSEPH SIMON, OF PHILADELPHIA, PENNSYLVANIA.

SUPPORT.

Application filed November 1, 1924. Serial No. 747,352.

This invention relates to supports, and more particularly to a supporting clip formed of spring material and adapted to be attached to a suitable support for holding 5 documents, papers, or analogous articles, securely in position, so that they may be quickly and easily removed, if desired.

Another object of the invention is to provide a support, as specified, which is simple 10 in construction, may be cheaply manufactured and one in which the inherent resiliency of the metal employed, is enhanced by the particular shape of the clip body, so as to provide firm and secure engagement 15 with the objects or articles to be supported.

Other objects of the invention will appear in the following detail description, and in the accompanying drawings wherein:—

Figure 1—is a front elevation of the improved support or clip.

Figure 2—is an edge elevation of the improved support or clip.

Figure 3—is a front elevation of a modified form of the support or clip.

Figure 4—is a side elevation of the modified form of the support or clip.

Referring more particularly to the drawings, the improved support or clip is constructed of spring sheet metal, and it comprises the attaching portion 1 which is formed integrally with the main body 2, the entire support being formed of a single piece of material. The attaching portion 1 comprises a pair of slightly spaced parallel sections 3 and 4, which are joined at the uppermost end of the support, and between which the head 5 of a suitable attaching tack 6 is engaged. The tack 6 extends through the inner section 4, and is adapted to be driven 40 into a support of any suitable type, as shown at A.

The support or clip extends outwardly substantially at right angles to the attaching portion 1 from the lower end of the outer side 3 of the attaching portion forming the substantially horizontal shoulder 7. From the horizontal shoulder 7, the main body 2 inclines downwardly and inwardly towards the support A, and it has its free lower end 50 slightly rolled, as shown at 8 to provide a non-abrasive article engaging end and also to provide a flaring entrance between the support or clip, and the permanent support A, so as to facilitate papers or analogous

articles to be slipped behind the spring body 55 or arm 2 of the support. The entire body of the support or clip is made of spring material, and the inherent spring action thereof is enhanced by the outward bending of the portion 7 and the corresponding inclining of the body or arm 2. Referring to Figure 2 of the drawings it will be seen that a tool or implement of some kind may be used to engage with the clip between the shoulder 7 and the part 3 of the clip, and by means 60 of several blows from a hammer, the clip can be bent or shaped at this point so as to greatly increase the tension of the part 2 of the clip, so that the surface engaging element 8 will greatly tighten against the stationary support A. In additionally bending the clip at this point will cause the part 3 to fulcrum on the head of the securing means 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540

In Figures 3 and 4 of the drawings, a modified form of the invention is shown in which the attaching portion 1' comprises only one thickness or layer of the metal, and the attaching pin 6' extends therethrough with the head engaging against the outer surface of the attaching portion 1'. If it is so desired, the body or arm 2' may be gradually decreased in width from the outwardly bent substantially horizontal shoulder 7' to the curved edge 8', without departing from the spirit of this invention.

It is, of course, to be understood, that the invention may be constructed in various other manners and the parts associated in different relations, and therefore, I do not desire to be limited in any manner, except as set forth in the claim hereunto appended.

What I claim is:—

As an article of manufacture, an article holding clip constructed from a simple strip of spring metal folded on itself at one end to provide two parallel parts, one of the parts constituting an attaching element for the reception of securing means to fasten the clip to a stationary support, the other part constituting a wearing covering or shield overlying the head of the securing means to prevent the head from forcing through the shield, said clip at a point beyond the shield being bent laterally and outwardly, said lat-

erally and outwardly bent portion being of substantial depth as to provide a substantial article abutment shoulder, the clip beyond the shoulder extending downwardly and inclined toward the stationary support, whereby said downwardly and inwardly extending part may be sprung laterally to permit of

a substantial number of thicknesses of articles to engage thereunder and therefore abut said shoulder to retain the articles in place and evenly disposed.

In testimony whereof I affix my signature.

PAUL JOSEPH SIMON.
